STEAM AND WATER TRAP

Martin E. Brunderman, Chicago, Ill.

Application April 14, 1939, Serial No. 267,771

5 Claims. (Cl. 237—78)

This invention relates to improvements in steam and water traps of the type adapted for attachment to air relief valves of steam radiators.

The escape of steam from the usual form of air relief valves for steam radiators has been a cause of great annoyance. The rising currents of air mingled with steam and moisture resulting therefrom, has rapidly disfigured the decoration of walls adjacent the radiator. Also, it is common for the steam to force some water out through air valve which in a relatively short time forms puddles of water on the floor adjacent that radiator. Also, the steam so emitted has been found to condense and settle on the furniture in the room where the radiator is located, thereby causing damage thereto.

The primary object of this invention is to remedy and overcome these inherent defects by providing an apparatus to trap the escaping steam and collect the resultant condensate.

Other objects of this invention are to provide a device of this character which will seat on and envelop an air relief valve for radiators; to provide in a device of this character, a condensate storage chamber; to provide a baffle plate for condensing the steam and thence directing it to a storage chamber; to provide a device of this character wherein the water so collected may be utilized by slowly humidifying the atmosphere through forced evaporation and discharge from the trap; to provide means for positive locking of the device directly to the relief valve; to provide means for insuring a tight fit of the device to the valve; to provide an indicating apparatus on the device to measure the water collected in the storage chamber; and to provide a device of this character which is simple in construction and operation and inexpensive to manufacture.

An illustrative embodiment of this invention is shown in the accompanying drawing, in which:

Figure 1 is a vertical middle cross-sectional view on line 1—1 of Fig. 2 through my improved steam trap shown with and attached to an air relief valve. The valve is shown attached to the end section of a radiator; the valve and radiator section being shown in full lines.

Fig. 2 is a vertical section taken on the line 2—2 of Fig. 1.

Fig. 3 is a horizontal section taken on the line 3—3 of Fig. 1.

Fig. 4 is a perspective view of my steam trap showing the rear side thereof which faces the radiator.

Referring in detail to the drawing, my improved steam trap comprises a specially-formed

shell or container 1, preferably of cast or forged metal, having integrally formed side and end walls 2, 3, 4 and 5 respectively; a metallic cylindrical shell 6 disposed centrally within the container 1 and integrally secured to the side wall 3 by any suitable means, such as by spot-welding or the like or it may be autogenously integral therewith; a cap 7 having a restricted opening 8 of sufficient diameter to permit the upper end 9 of an air relief valve 10 to be inserted therein, 10 which cap may be integral with part 6; a removable cover plate or cap 11 having downwardly-extending flanges 12, the outer faces of which abut against the adjacent inner faces of the side and end walls 2, 3, 4 and 5 to provide for snugly seating the cover plate 11 on the container 1; and a water level indicating means 13 comprising a float 14 and a gage rod 15.

The container 1 has a vertical slot 16 extending from the bottom 17 upwardly to a point just 20 above the center of the container. This slot extends through the wall and is of sufficient width to accommodate the stem 19 of the air relief valve 10.

The upper portion of cover plate 11 is arched 25 lengthwise at 20, the highest point of which is directly over the upper end 9 of valve 10. This plate serves to deflect the steam and water ejected from valve 10, into the container chambers 21 and 22 mutually connected at crevice 1'. 30 The cover plate 10 is also provided at each end with a group of apertures 23 through which moisture of evaporation from the water in chambers 21 and 22, may escape into the atmosphere; and therefore the device as a whole may be also called 35 a humidifier. A slot 24 is also formed in the cover 11 through which the indicating rod 15 is inserted so that any movement of the rod 15 will be in a vertical plane.

The cap 7 is formed with a downwardly projecting portion or a flange-like member 25 which is arranged to snugly seat in the upper end of the cylindrical shell 6. It is to be understood, however, that this cap 7 may be formed integrally with or be a part of the shell 6. It is important 45 that the cap 7 be so seated in the shell 6 that the same will not readily become disengaged therewith, as the inner face of the cap 7 forms a bearing seat which rests on the upper end 26 of the air relief valve 10. Thus it will be apparent that 50 the entire weight of the container 1 is borne by this cap 7 and hence it is important that the same be secured to the shell 6 in such a manner that it will not be readily displaced.

In order to insure firm steadiness of the en- 55

tire unit and to preclude rocking or vibration, a pair of cup-shaped washers 27 and 28 of a diameter substantially the same as the inner diameter of the shell 6 are set in said shell directly 5 below the relief valve 10, so that the upper face of washer 27 bears against the lower end 29 of said valve 10 and the lower face of washer 28 bears against the rod 30, the purpose of which rod will hereinafter be described. A helical compression spring 31 is placed between the washers 27 and 28 to keep them spread apart and to provide for solidity of the device as a whole by holding the trap snugly down on the valve 10.

The bottom 17 of the container 1 is substantially thicker than the side and end walls thereof. A medial transverse reception slot 32 is drilled through the wall 5 and substantially entirely through the bottom 17 in the manner shown in Fig. 2 and is tapped adjacent the open end of 15 the slot as at 32'. This is to receive the said rod 30, which is provided with threads 33 at the headed one end thereof. It will now be apparent that this rod being threaded, as shown, prevents pilferage of the device without first removing 20 the rod and therefore acts as a semi anti-theft device as well as a bearing for the washer 28.

In assembling the device on a radiator, the rod 30, spring 31 and washers 27 and 28 are first removed. The device is then placed over the air relief valve 10 and guided into position by means 30 of the slot 16 in wall 3. The washer 27 and the washer 28 and the spring 31 are then replaced and the rod 30 threaded in the slot 32. The device is now ready for use.

35 In operation, when steam and water are ejected from the air relief valve through the upper end 9 thereof, they will strike the arch 20 of the cover plate 11 and be deflected into the intercommunicating chambers 21 and 22. The steam will, under ordinary circumstances, condense into water when it strikes the dome 20 and will fall into the chambers 21 and 22. The device is so constructed and arranged that the drippings will only collect in the chambers 21 and 22.

40 The float 14 of the indicating means 13 will rise with the level of the water in the chambers as it increases; and by ready observation it will be seen when the container 1 is filled with water 50 and needs attention.

Because the container 1 will absorb part of the heat emanating from the radiator 34, the container will become warm and under ordinary circumstances the heat absorbed by the water in the container is sufficient to cause the water to evaporate and escape into the atmosphere through the apertures 23 in the cover plate 11, thereby appreciably humidifying the room.

For humidification purposes, if the steam and 60 water emitted from the valve 10 is insufficient to automatically partially fill the container 1, the container may be partially filled with water from outside sources at any time as by merely removing the cover plate 11 and manually pouring in 65 water.

It is to be understood that even though the

device described herein is preferably constructed of metal, it may be constructed of any suitable material which is durable, such as Bakelite, or like material.

It is to be understood that some of the details set forth may be altered or omitted without departing from the spirit of the invention as defined by the following claims.

I claim:

1. In a device of the class described, the combination of an air relief valve for steam radiators, and a steam and water trap therefor comprising a body having an arcuate cover therefor, a cylindrical shell disposed substantially centrally in said body, said body and shell having a mutual longitudinal slot therein to receive the stem of said valve, and means on said shell for seating said body on said valve.

2. In a device of the class described, the combination of an air relief valve for steam radiators, and a steam and water trap therefor comprising a body having an arcuate topped cover therefor, a cylindrical shell disposed substantially centrally in said body, said body and shell having a mutual longitudinal slot therein to receive the stem of said valve, and resilient means to positively secure said body to said valve.

3. In combination with an air relief valve for steam radiators, a combined humidifier and steam and water trap comprising a storage chamber, a centrally disposed cylindrical shell in said chamber having a seat, said shell being formed and arranged to receive and envelop said valve, said shell and chamber having a mutual longitudinal slot in their side walls adapted to receive the stem of said valve; and means for securing said chamber to said valve.

4. In combination with an air relief valve for steam radiators, a combined humidifier and steam and water trap comprising a storage chamber including a cap therefor of arch-like design, a centrally-disposed cylindrical shell in said chamber having a seat, said shell being formed and arranged to receive and envelop said valve, said shell and chamber having a mutual longitudinal slot in their side walls adapted to receive the stem of said valve; and resilient means for securing said trap to said valve.

5. A radiator attachment comprising a shell of oblong plan formed with a central hollow core open at the bottom to receive bodily the relief valve of a household type of radiator, said core on one side being integral with a side wall of said shell where a slot extends upward from the bottom to admit the stem of the valve, the top wall of said core being centrally perforated to admit the exhaust head of the valve, there being open space above said core communicating with the spaces at the sides respectively of said core, the top of said shell being perforated for the escape of steam and the top of said core about its perforation serving as a bearing for resting said attachment on the top part of the radiator valve.
